EXTRACTORS FOR GUNS WITH VERTICAL-
LY SLIDING BREECH BLOCKS

William Summerbell, Washington, D. C.

Continuation of application Serial No. 393,763,
May 16, 1941. This application June 23, 1944.
Serial No. 541,805.

5. Claims. (Cl. 89—24)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to an extractor mechanism for a gun of the type having a vertically sliding breech block. The extractor mechanism which is the subject of this invention performs two functions, that of extracting the fired cartridges and of serving as detent means for retaining the breech in open position preparatory to insertion of a fresh round. Broadly, extractor mechanisms capable of performing these functions have been used in the prior art but it is not believed that an extractor device which is as safe and positive in its action as the present invention has heretofore been used.

It is the object of this invention to provide an extractor mechanism which will be positive and reliable in its functioning and at the same time be practically incapable of accidentally releasing the block from open position.

It is a further object to simplify manufacture.

It is a further object to provide an extractor mechanism capable of ready assembly and disassembly.

The specific nature of the invention as well as other objects and advantages thereof will clearly appear from a description of a preferred embodiment as shown in the accompanying drawings in which:

Figure 1 is a side elevation partly in section of a gun embodying this extractor mechanism. The breech is shown in closed position.

Figure 2 is an end elevation sectionalized on the line 2—2 of Fig. 1.

Figure 3 is a side elevation, partly in section with the breech in open position.

Figure 4 is a top plan view, partly in section, and

Figures 5 and 6 are respectively side and end elevations of one of the extractor arms.

Referring to the drawings by characters of reference, there is shown a breech ring 1, having an opening receiving a vertically sliding breech block 2, the mechanism for operating the block being omitted as it forms the subject matter of my co-pending application, Serial No. 393,762, filed May 16, 1941 for Breech block mechanism now Patent No. 2,398,453, issued April 16, 1946.

Extractor arms 3 and 4, Figs. 5 and 6, are provided in their central portion with bearing bores 7 and 8, respectively, adapted to cooperate with trunnion pins 5 and 6 driven into holes formed in the breech ring, the extractor arms rotating upon

these fixed pins. The upper ends of the extractor arms are provided on their inner faces with opposed fingers 9 and 10, to engage the rim of a cartridge case inserted in the chamber. At their lower ends the extractor arms are provided with opposed lugs 11 and 12 which are adapted to travel in tracks 17 provided in the faces of the breech block. The forward edge of each extractor arm in the section opposite the trunnion is formed with a cam surface 13 adapted to engage a plunger 14 mounted in a bore 15 in the breech ring and pushed outwardly by a spring 16. Each plunger is provided with a vent 14a for equalizing the pressure between bore 15 and the atmosphere permitting free movement of the plunger in the bore. The surfaces 13 are so formed that springs 15 tend to maintain the upper ends of the extractor arms in a position of rest away from the rear face of the barrel, which position is referred to as the rearward rest position and is shown in Fig. 3.

Referring particularly to Fig. 3, each axis of plunger 14 and each axis of rotation of extractor arm 3 lie in the same plane and at right angles to each other. The face 14b of plunger 14 is substantially plane and positioned at right angles to the axis of the plunger. Cam surface 13 of each extractor arm also is substantially plane and is disposed at right angles to the axis (extended) of the plunger when the extractor arm is in its aforementioned rearward rest position. It will be observed that, with this arrangement, angular displacement, in either sense, of the extractor arm from rest position about either pin 5 or 6 will cause the plunger to be depressed in its bore against the action of spring 16, thereby setting up a counter force tending to restore the extractor to its rearward rest position. This described interaction of plunger and extractor arm tends to maintain each extractor arm at rest in rearward position against vibrational and shock forces set up in the mechanism in operation. In the particular form disclosed, the aforesaid vibrational and shock forces are largely occasioned by collision of the lower end of the extractor arms 3 and 4 with crank shaft 20 upon overrunning by the extractor arm of its rearward rest position.

The construction and arrangement of extractor arm, pin and plunger permits of ready removal of the arm from the pin and its reassembly thereto. As best explained in connection with Fig. 2, after removal of the breech block, arm 3 may be removed from its pin 5 by simple withdrawal to the right and extractor arm 4 from its pin 6 by movement to the left. After removal of an extractor arm, plunger 14 will be moved rearwardly by the

action of spring 16 until such movement is arrested by abutment of the plunger face against the forward surface of its adjacent pin 5 or 6. Pins 5 and 6 thus each acts as a stop means preventing ejection of the plunger from bore 15. It will be observed from Figure 2 that each plunger 14 is so positioned relative to the ends of pins 5 and 6 that a portion of its face 14b is offset and is exposed at the right of pin 5 or at the left of pin 6 for a purpose now to be described.

In fitting the extractor arm upon pin 5, it is necessary that plunger 14 be depressed sufficiently far in its bore to permit cam surface 13 to clear the face of the plunger 14 when bearing bore 7 is aligned with pin 5. This is accomplished in my construction by placing cam surface 13 against the exposed portion of the plunger face 14b and forcing it and thereby the plunger forwardly by pushing the extractor arm forward until its bearing bore is in alignment with pin 5 or 6, whereupon the extractor arm 3 is moved to the left (Fig. 2) to position the same upon its pin 5 or to the right for pin 6, the cam surface 13 meanwhile retaining the plunger in forward position and clear of the body of the extractor arm.

The opposite sides of the breech block are provided on their forward portions with like tracks 17 for engagement with the lugs 11 and 12 on the extractor arms. In a section of each track which will engage the corresponding lug shortly before the block reaches the lower limit of its downward travel, a cam surface 18 is provided to rotate the extractor arms about their trunnions. During such rotation the fingers 9 and 10 will engage the rim of the cartridge case in known manner for extraction thereof. In the front edge of each track 17 a stop lug 19 is provided to engage with the lower plane surfaces 22 and 24 of the lugs 11 and 12 serving to retain the breech block in a position slightly above the limit of its downward travel.

In operation the breech block is lowered after firing by means not shown. Shortly before the block reaches its lowermost position, the cam surface 18 in each of the tracks engages the rounded surfaces 25 and 26 on the lower lugs 11 and 12 on the extractor arms and drives them forward to extract the cartridge case. The springs provided will tend to maintain the arms in this rearward rest position and as the block begins to rise under the influence of the block operating mechanism, its progress will be stopped by the engagement of the plane surfaces 22 and 24 on the extractor arm lugs with the stop lug surfaces 21 provided in the breech block tracks 17. As a fresh cartridge is inserted its rim will engage the fingers 9 and 10 on the upper ends of the extractor arms tending to move them forwardly to disengage the stop lugs 19 to free the block 2 to rise to the closed position. It will be noted that the extractor arms 3 and 4 are independent of each other and that they have independent engagement with the breech block. This is an important safety feature, as the block operating mechanism of such semi-automatic weapons functions with sufficient violence while, if the breechblock 2 were inadvertently released, will cause injuries to the hands of the operator. Should one of the extractor arms 3 or 4 be disengaged inadvertently during cleaning or the like, the other will retain the block 2 in a downward position. The arms 3 and 4 must be disengaged simultaneously, as by the rim of a cartridge case when loading the weapon, to release the block. The spring-pressed plunger 14 maintains the extractor arms 3 and 4

in a rear dead position, and tends to obviate the possibility of the extractor arm lugs 11 and 12 from bouncing or vibrating out of engagement with the stop lugs 19 on the breechblock 2 during rapid fire actuation of the breech mechanism by damping the movements of the extractor arms.

It will be noted that assembly of the extractor mechanism may be effected without the use of tools and that the extractor arms after having been put in place on their trunnions, are retained thereon by engagement with the sides of the breech block which is inserted after the arms are on the trunnions.

This application is a continuation of my co-pending application Serial No. 393,763, filed May 16, 1941, for "Extractors," now abandoned.

I claim:

1. In a gun comprising a breech ring, a breech block reciprocably mounted therein between an open and a closed position, an extractor arm, means pivoting the same in said breech ring for oscillation between a forward and rearward rest position, said arm having means adapted to engage a cartridge case for extracting the latter after firing, cooperating cam surfaces on said breech block and extractor arm for rotating said extractor arm about its pivot means to a rearward rest position for extracting the cartridge case upon opening of the breech, a stop lug on the breech block and a cooperating lug on the extractor arm adapted to engage in its rearward rest position the stop lug of the breech block to lock the same in open position, a plunger slidably positioned in said breech ring for movement toward said pivot means and having a cam face thereon, means yieldably urging said plunger towards said pivot means, and a second cam surface upon said extractor arm engaging said cam face on said plunger, said cam face and said second cam surface being in contact with and at an acute angle to each other when said extractor arm is in its forward position whereby said spring-pressed plunger surface is adapted to urge said second cam surface into parallelism with said cam face thereby preventing the return motion of said extractor from a rearward rest position and said cam face and said second cam surface being so constructed and arranged relative to each other that angular displacement of said extractor arm from its rearward rest position will move said plunger against the force of said yieldable urging means, thereby setting up counter forces tending to restore said extractor arm to its rearward rest position.
2. In a gun comprising a breech ring, a breech block reciprocably mounted therein between an open and a closed position, an extractor arm, means pivoting the same in said breech ring for oscillation between a forward and rearward rest position, said arm having means adapted to engage a cartridge case for extracting the latter after firing, cooperating cam surfaces on said breech block and extractor arm for rotating said extractor arm about its pivot means to a rearward rest position for extracting the cartridge case upon opening of the breech, a stop lug on the breech block and a cooperating lug on the extractor arm adapted to engage in its rearward rest position the stop lug of the breech block to lock the same in open position, a plunger slidably positioned in said breech ring for movement toward said pivot means and having a plane cam face thereon perpendicular to the line of movement of said plunger, means yieldably urging said

plunger towards said pivot means, and a second plane cam surface upon said extractor arm positioned to engage said cam face on said plunger, the plane of said second cam surface being normally perpendicular to the line of movement of said plunger, whereby angular displacement of said extractor arm from its rearward rest position will move said plunger against the force of said yieldable urging means, thereby setting up counter forces tending to restore said extractor arm to its rearward rest position.

3. In a gun, the combination of a breech ring having a recess to receive a sliding breechblock, a pivot, an extractor arm pivoted thereon for movement between a forward and a rearward position, a plunger mounted for reciprocation in said breech ring, said plunger having a flat surface lying in a plane parallel to the axis of said pivot, a cam on said extractor arm cooperating with said plunger face and said cam having a flat surface lying in a plane parallel to the pivot axis of said extractor arm, said surfaces being in contact and forming an acute angle with each other when said extractor arm is in its forward position whereby said extractor arm is forced to a rearward position, said surfaces being in face-to-face contact and parallel with each other when said extractor arm is in its rearward position whereby said extractor arm is releasably held in said rearward position.

4. In a gun, the combination of a breech ring having a recess to receive a sliding breechblock, a cam groove on said breechblock, a stop lug at one end of said groove, a pivot, an extractor arm pivoted thereon for movement between a forward and a rearward position, a cam follower on said extractor arm actuated by said breechblock cam groove to rotate said extractor arm to a rearward position, a stop means on said extractor arm adapted to engage said stop lug when said extractor arms is in a rearward position to hold said breechblock against movement in one direction, a plunger mounted for reciprocation in said breech ring, said plunger having a flat surface lying in a plane parallel to the axis of said pivot, a cam on said extractor arm cooperating with said plunger face, said cam having a flat surface lying in a plane parallel to the pivot axis of the extractor arm, said surfaces being in contact and forming an acute angle with each other when said extractor arm is in its forward position, said surfaces being in face-to-face contact and parallel with each other when said extractor arm is in its rearward position whereby said plunger releasably holds said extractor arm in said rear-

ward position causing said stop means to engage said stop lug.

5. In a gun, the combination of a breech ring, a breechblock reciprocably mounted therein, a cam groove in said breechblock extending lengthwise thereof, a stop lug on said breechblock adjacent said cam groove, a pivot on said breech ring extending substantially at right angles to the path of movement of said breechblock, a bore in said breech ring extending substantially at right angles to said pivot, a plunger in said bore having a portion thereof extending transversely beyond the end of said pivot, spring means in said bore abutting said plunger for forcing the same toward said pivot, an extractor arm pivoted on said pin and adapted to be moved thereon from a forward to a rearward position, follower means on said extractor arm cooperating with said cam groove for moving said extractor arm to a rearward position, said plunger having a flat end cam surface substantially parallel to the axis of the pivot, a flat cam surface on said extractor extending substantially parallel to said pivot axis whereby when said extractor is in its forward position said cam surfaces form an acute angle with each other and when said extractor is in its rearward position said cam surfaces are parallel and in face-to-face contact with each other whereby said spring-pressed plunger yieldingly holds said extractor arm from movement from a rearward to a forward position, a stop surface on said extractor arm adjacent said follower means adapted to engage said stop lug whereby upon reciprocation of the breechblock in one direction the extractor arm will be rotated to a rearward position to extract a cartridge case and place said stop surface into engagement with said stop lug thereby holding the breechblock against reciprocation in a reverse direction.
